[57] CLAIM

The ornamental design for a travelers case for portable vacuum cleaner, as shown and described.

DESCRIPTION

FIG. 1 is a perspective view of a travelers case for a portable vacuum cleaner showing my new design;

FIG. 2 is a rear elevational view thereof;

FIG. 3 is a bottom plan view thereof;

FIG. 4 is a left side elevational view thereof; and

FIG. 5 is a perspective view of the case showing the interior thereof.
